UNITED STATES PATENT OFFICE.

JOHN J. SULLIVAN, OF PARSONS, PENNSYLVANIA.

DRAFT DEVICE AND SPARK-ARRESTER.

1,105,466.

Specification of Letters Patent. Patented July 28, 1914.

Application filed September 3, 1913. Serial No. 787,951.

To all whom it may concern:

Be it known that I, JOHN J. SULLIVAN, a citizen of the United States, residing at Parsons, in the county of Luzerne and State of Pennsylvania, have invented new and useful Improvements in Draft Devices and Spark-Arresters, of which the following is a specification.

This invention is an improved draft device and spark arrester for use in connection with a locomotive or stationary steam engine, for promoting the draft and for arresting sparks and, hence, obviating danger of conflagrations by sparks from the engine, the invention consisting in the construction, combination and arrangement of devices hereinafter described and claimed.

The object of my invention is to provide an improved draft device and spark arrester which is simple and cheap in construction, and which may be readily installed and the parts of which may be readily adjusted and disassembled.

In the accompanying drawings: Figure 1 is a vertical central sectional view of a draft device and spark arrester constructed in accordance with my invention, showing the same arranged in the smoke box of a locomotive and in operative relation to the exhaust pipe and stack of the locomotive. Fig. 2 is a horizontal sectional view of the same on the plane indicated by the line *a—a* of Fig. 1. Fig. 3 is a similar view on the plane indicated by the line *b—b* of Fig. 1. Fig. 4 is a vertical central sectional view of a modified form of my improved draft device and spark arrester, arranged for use in connection with the steam or exhaust pipe and stack of a stationary engine.

Referring first to the form of my invention shown in Fig. 1, and in which the draft device and spark arrester is arranged in a locomotive smoke box, there is shown for the purposes of this specification a locomotive smoke box at 1 the exhaust pipe being indicated at 2 and the stack at 3. The exhaust pipe is provided at its upper end with a flange 4.

In accordance with my invention, I provide a nozzle box 5 which is adapted to fit in the upper end of the exhaust pipe and has a base flange 6 to bear on the flange 4 and which is detachably secured thereto as by means of suitable bolts 7. The nozzle

box is provided with a vertical central bore 55 which registers and is connected with the bore of the exhaust pipe 2 and on the upper side of the nozzle box, at the center thereof, is a vertically arranged upwardly directed nozzle 9 which is formed with a threaded 60 base 10 that is screwed in a countersunk portion of the bore of the nozzle box. The nozzle box is also formed with a series of radially arranged and upwardly extending elbows 11, four of such elbows being here 65 shown and the said elbows being spaced at intervals of 90°. To each elbow is screwed or otherwise secured the lower end of a vertically arranged blow pipe 12. Each blow pipe is provided with a lower vertically adjustable collar 13 and an upper vertically adjustable collar 14, the collars being, respectively, provided with set screw 15—16. I also provide a draft pipe 17, the diameter of which is somewhat less than the width 75 of the space between the blow pipes 12, so that the said draft pipe is adapted to be arranged between the blow pipes and the draft pipe is provided at its lower end with a flared or frusto-conical intake portion 18 80 which has openings through which the blow pipes 12 extend, the said draft pipe being arranged concentrically with relation to the nozzle 9. At the lower intake end of the draft pipe is a screen 19 which is preferably 85 made of wire netting but which may be made of any suitable foraminous material. This screen rests on the lower collars 13 and, hence, the said draft pipe 17 is vertically adjustable on the blow pipes 12, the said 90 collars being adapted to be secured to the blow pipes at any desired adjustment by the set screws 15, as will be understood.

Since the blow pipes 12 pass directly through openings in the enlarged intake portion or lower end of the draft pipe, the said blow pipes also form supports and vertical guides for the draft pipe to hold the latter in place and yet permit it to be adjusted as may be required. I also provide a second 95 draft pipe 20 which is of greater diameter than the draft pipe 17 and is arranged concentrically therewith and at the upper end thereof, the upper end of the draft pipe 17 being arranged in the center of the flared 100 intake portion 21 of the second draft pipe and the upper ends of the blow pipes 12 being also worked in the lower end of the

second draft pipe and between the wall thereof and the draft pipe 17. The enlarged intake end 21 of the second draft pipe is also provided at its lower end with a screen 22 which is similar to the screen 19 and has openings through which the blow pipes 12 extend. The said screen 22 rests on the upper collars 14 of the blow pipes and, hence, the upper or second draft pipe is vertically adjustable with respect to the first or lower draft pipe 17, the set screws 16 permitting vertical adjustment of the supporting collars 14 of the second draft pipe. It will be observed and understood that the upper end of the draft pipe 17 discharges into the lower end of the second draft pipe 20. The upper end of the second draft pipe is arranged concentrically with respect to the stack 3 and discharges into the lower end thereof.

In the operation of my improved draft device and spark arrester, the exhaust steam from the locomotive engines is discharged from the exhaust pipe 2 into the nozzle box 5 and directly and upwardly therefrom lower flared or enlarged end 18 directly through the nozzle 9 into and upwardly through the center of the draft pipe 17, thus setting up such draft and suction in the draft pipe 17 as to cause the same to draw in the smoke and products of combustion from the smoke box and discharge the same upwardly in the second draft pipe 20. The screen 19 arrests sparks, pieces of live coal and the like and prevents them from being blown out through the stack. The upward blast of the exhaust steam through the upper draft pipe 20 and the blasts of exhaust steam which are directed upwardly through the second draft pipe also by the blow pipes 12, cause the upper draft pipe also to suck in smoke and products of combustion at its lower end and discharge the same up to the stack, the upper screen 22 serving to arrest the sparks and the like.

By the use of my improved draft device danger from sparks is entirely eliminated. In the form of my invention shown in Fig. 4, the nozzle box 5^a is arranged at the upper end of the exhaust or steam pipe 2^a of a stationary engine, and the draft pipe 17^a is arranged with the screen 19^a at its lower flared or enlarged end 18^a directly around the center nozzle 9^a and the blow pipes 12^a extend up through openings in the flared enlarged lower portion of said draft pipe. The draft device as well as the steam pipe 2^a are located in a stack which is here indicated at 24 and it will be understood that the draft device promotes draft through the stack and also causes the sparks to be arrested by the screen 19^a.

In both forms of my invention, the screen may be dispensed with if it is not desired to arrest sparks and is only desired to em-

ploy the draft device. The invention may also be used under the fire or grates on all boilers.

I claim:—

1. A draft device of the class described comprising a nozzle box adapted to be connected to the exhaust pipe of a steam engine and having an upwardly directed nozzle and also provided with upwardly directed blow pipes, in combination with a draft pipe having a flared or enlarged intake lower end, the said draft pipe being arranged above the nozzle box so that the nozzle of the nozzle box discharges upwardly through the draft pipe and the said blow pipes discharge upwardly around and without the said draft pipe, the said blow pipes extending upwardly through the enlarged intake lower portion of the draft pipe and being provided with supporting means for said draft pipe.

2. A draft device of the class described comprising a nozzle box adapted to be connected to the exhaust pipe of a steam engine and having an upwardly directed nozzle and also provided with upwardly directed blow pipes, in combination with a draft pipe having a flared or enlarged intake lower end, the said draft pipe being arranged above the nozzle box so that the nozzle of the nozzle box discharges upwardly through the draft pipe and the said blow pipes discharge upwardly around and without the said draft pipe, the said blow pipes extending upwardly through the enlarged intake lower portion of the draft pipe and being provided with supporting means for said draft pipe, and the said draft pipe being vertically adjustable on said blow pipes.

3. A spark arrester and draft device of the class described comprising a nozzle box adapted to be connected to the upper end of an exhaust steam pipe and provided with an upwardly directed nozzle and also with upwardly directed blow pipes spaced from the nozzle, in combination with a draft pipe having an enlarged intake lower end and arranged above the nozzle box, the said nozzle being arranged to discharge upwardly through the draft pipe and the said blow pipes being arranged around and without said draft pipe, and a second draft pipe of greater diameter than the first named draft pipe and having an enlarged intake lower end in which the upper end of the first-named draft pipe is arranged.

4. A spark arrester and draft device of the class described comprising a nozzle box adapted to be connected to the upper end of an exhaust steam pipe and provided with an upwardly directed nozzle and also with upwardly directed blow pipes spaced from the nozzle, in combination with a draft pipe having an enlarged intake lower end and arranged above the nozzle box, the said

nozzle being arranged to discharge upwardly through the draft pipe and the said blow pipes being arranged around and without said draft pipe, and a second draft pipe 5 of greater diameter than the first-named draft pipe and having an enlarged intake lower end in which the upper end of the first-named draft pipe is arranged, each of the draft pipes having a screen at its lower

intake end through which the said blow 10 pipes extend and have vertical adjustment on said blow pipes.

In testimony whereof I affix my signature in presence of two witnesses.

JOHN J. SULLIVAN.
